BOILER ATTACHMENT

Application filed April 2, 1924. Serial No. 703,829.

The present invention relates to improvements in boiler attachments and more particularly to devices designed for use in blowing the soot out of the tubes of the boiler.

It is well known that a deposit of soot tends to accumulate in boiler tubes. This soot is one of the best heat insulators known, and even a very thin coating of soot brings about considerable heat loss, thereby reducing the efficiency of the boiler. It is, therefore, desirable for efficient operation to frequently clean this soot from the tubes. This operation has generally been neglected by the operating force in the boiler room on account of heavy labor required and excessive heat present in cleaning the soot with the less expensive devices usually available for the purpose. The installation of effective soot-blowing apparatus heretofore available has been very expensive and therefore comparatively seldom used.

Devices for blowing soot, heretofore available, have, in general, involved the use of fixtures permanently mounted adjacent the boiler tubes, and these fixtures, besides being expensive to install, require inspection and deteriorate rapidly. In some cases they require the closing up of a boiler tube, thereby lowering the efficiency of each furnace of the boiler and inviting corrosion and scale.

The present invention contemplates boiler attachments, by means of which one can readily clean the soot from the boiler tubes without great effort. It also contemplates a soot blowing arrangement by which the boiler may be cleaned at frequent intervals without the necessity of shutting down the boiler, opening the smoke doors, or cutting the boiler off the steam line. It also contemplates the provision of a soot blowing device which utilizes a jet of steam introduced into the combustion chamber to blow the soot in the direction of the draft, and the removal of the device for producing the steam jet upon the completion of the blowing of the soot.

The devices heretofore in use have generally required installation of the complete soot blowing attachments for each furnace of the boiler. The present invention, on the other hand, provides for a simple attachment

for each furnace in the boiler, which can be installed in an inexpensive manner, and the use of a single device which may be introduced into any of the furnaces to blow the tubes thereof. In this manner, the installation expense is much lower because a single soot blowing device may be utilized to blow all the boilers in the power plant or on board the ship.

The accompanying drawings show, for the purposes of illustrating the invention, one of the many possible embodiments in which the present invention may take form.

In these drawings:

Fig. 1 is a longitudinal sectional view through the soot blower;

Fig. 2 is a cross section on the line 2—2 of Fig. 1; and

Fig. 3 is a diagrammatic view showing the use of the blower in a conventional boiler.

For the purpose of illustrating the invention, the same is shown in use in a Scotch marine type boiler. It is, of course, obvious that the invention is in no wise limited to this type of boiler as it is capable of general application. The boiler here illustrated has the conventional heating section 11, made up a plurality of tubes, the furnace 12, combustion chamber 13, water leg 14, smoke box 15, and uptake 16. The smoke box door 17 is provided with attachments, designated generally by the letter A, which include a tubular member substantially in alignment with one of the central tubes of each furnace of the boiler.

The soot blowing device shown in detail in Figs. 1 and 2 is adapted to be inserted through the smoke-box door and one of the tubes of the heating section so that the nozzle end of the blower extends into the combustion chamber.

A tubular member 18 here shown in the form of a length of hose 18' coupled to an inner piece of pipe 19. It is adapted to reach from in front of the smoke-box door into the combustion chamber. The length of the pipe is such that a substantial length of pipe remains in a boiler tube. The inner end 19' of this pipe is here shown as being threaded into an outer tubular member 20, and an inner tubular member or shell 21 is slidably

and rotatably mounted inside the outer tubular member. The parts 19 and 20 are preferably, though not necessarily made separate. They may be integral if desired.

5 The left end 22 of the shell 21 is here shown as being threaded into the open end of a revolvable head 23, but these parts may likewise be integral if desired. The shell and head are however, preferably made of two 10 separate steel castings. The head may be cast hollow, a hole being provided in the end to accurately center the core so that the walls of the head may be made thin. This hole is later tapped and plugged as shown at 15 24. The head is provided with a side recess 25 at the foot of which there is an obliquely disposed hole 26, preferably threaded as shown to accommodate an externally threaded tubular nozzle 27. The nozzle is preferably 20 separate from the head so that it may be more accurately machined and so that different sized nozzles may be used. It may be provided with saw cuts 28 to facilitate threading it in or out of the hole 26.

23 As here shown the inner and outer tubular members 20 and 21 are provided with shoulders 29 and 30 to limit the sliding movement of these parts, and prevent the accidental removal of the revolvable head. In order to 28 provide a steam tight joint between these parts there may be provided a piston ring 31, and the outer member may be provided with grooves 33 to reduce the bearing surface and to receive oil if desired.

33 The right hand end 34 of the hose 18' is connected by an ordinary hose coupling 34^a to one end 35 of a T or valve casing 36, while a bushing 37 may be clamped to the other end 38 of the casing by a nut 39 as shown. A driving 40 shaft 40 is rotatably carried in the bushing and is made steam tight by a stuffing box 41 held tight by a cap 41' threaded onto the bushing. The shaft 40 extends outside the stuffing box and is connected to an operating 45 means in the form of a crank 42 adjustably locked onto the shaft. The side 43 of the casing is connected to a steam supply hose 43' through the medium of an ordinary steam hose coupling 43^a so that steam is introduced 50 into the chamber formed by the casing and parts connected thereto. One may conveniently make up this structure from a 90° valve, by removing the valve seats and substituting the driving shaft for the valve stem.

53 The steam pressure reacting against the head 23 will tend to force the shoulder 30 against the shoulder 29. This is prevented, and the head is made rotatable by drivingly connecting the shell 21 to the driving shaft 40 by a flexible shaft 44 which extends between them inside the tubular member, hose, and casing 36. One end 45 of this shaft is pinned to a sleeve 46 threaded and pinned onto the inner end 47 of the driving shaft, 60 while the other end 48 is pinned to a coupling

49 threaded into a boss 50 carried on a yoke 51 at the inner end of the shell 21. The thrust produced by the steam or compressed air inside the casing is transferred through this flexible shaft to the operating shaft 40 and is imposed onto the casing by the hub 42' of the crank engaging the cap 41'. Oil may be applied here, as this is the only wearing place subject to heavy load.

75 The operation of the soot blower is as follows: The revolvable head and attached tubing are inserted through a hole in the smokebox door (or through the tubular member A, if one is provided) and through the boiler tube so as to bring the revolvable head into the combustion chamber, somewhat as indicated in Figure 3. Steam (or compressed air) is turned on and escapes at high velocity through the nozzle. This escaping jet of steam is directed toward the adjacent header 80 of the boiler where it enters a tube and cleans the soot off the tube wall, the soot being carried away in the direction of the draft. The operator turns the crank 42 and thereby turns the shafts 40 and 44 so that the revolvable head and nozzle are rotated to direct the jet of steam through a conical path and reach a circular zone of boiler tubes. The entire blower may be reciprocated back and forth 85 in the boiler tube and thereby cause the jet to reach tubes at varying distances from the central tube. The nozzle is supported by the pipe 19 a substantial length of which is in the boiler tube. In this manner all the tubes in the furnace may be cleaned. After the operation has been completed in one furnace, the blower may be removed to another furnace or stored as desired.

90 The present embodiment of the invention 105 contemplates the use of a hose 18' between the T and the pipe 19, as the hose is flexible and permits the insertion of the blower in cramped locations common on shipboard. Where the room would permit, one could use 110 a piece of pipe, and a rod instead of the flexible shaft 44.

115 It will be noted that the flange 53 on the inner end of the shaft 40 will prevent the accidental removal of the shaft, should the flexible shaft break. This flange, together with the shoulders 29 and 30 prevent scalding in case the flexible shaft breaks.

120 Some boilers are provided with a tubular member expanded into the water leg of the boiler in line with the furnace, and in this case one may, if desired, use a soot blower having the nozzle disposed in the other direction, and insert it into the combustion chamber through the water leg. In this case it might be more convenient to provide a 125 short unitary casing instead of the multiple part tubular member and hose.

130 While I have described the soot blower as being operated by steam, it is, of course, obvious that one could use compressed air, if

desired. The term "steam" is used in the claims merely as a designation for a suitable operating medium.

It is obvious that the invention may be embodied in many forms and constructions, and I wish it to be understood that the particular form shown is only one of the many forms. Various modifications and changes being possible, I do not limit myself in any way with respect thereto.

What is claimed is:

1. A soot blower adapted to be entirely removed from a boiler or furnace for use in another boiler or furnace and structurally independent thereof, said soot blower having a tubular member adapted to be inserted through a tube leading to the combustion chamber of a boiler, a hollow shell revolvably carried inside the tubular member, a head supported by said shell and projecting out of one end of the tubular member and provided with a jet-forming nozzle, a casing having a steam inlet and attached to the other end of the tubular member, a driving shaft rotatably supported by the casing, a flexible shaft connected to the shell and the driving shaft, the flexible shaft transferring to the driving shaft the pull exerted by the steam reacting against the revolvable head, and a device for transferring said pull from the driving shaft to the casing.

2. A soot blower adapted to be entirely removed from a boiler or furnace for use in another boiler or furnace and structurally independent thereof, said soot blower having a tubular member adapted to be inserted through a tube leading to the combustion chamber of a boiler, a hollow shell revolvably and slidably carried inside the tubular member, a steam tight packing interposed between the shell and tubular member, a head supported by said shell and projecting out of one end of the tubular member and provided with an obliquely disposed jet-forming nozzle, a casing having a steam inlet and attached to the other end of the tubular member, a driving shaft rotatably supported in the casing, a flexible shaft connected to the shell and the driving shaft, the flexible shaft transferring to the driving shaft the pull exerted by the steam reacting against the revolvable head, and a device for transferring said pull from the driving shaft to the casing.

3. A soot blower adapted to be entirely removed from a boiler or furnace for use in another boiler or furnace and structurally independent thereof, said soot blower having a tubular member adapted to be inserted through a tube leading to the combustion chamber of a boiler, a hollow shell revolvably and slidably carried inside the tubular member, a steam tight packing interposed between the shell and tubular member, a nozzled head threaded to the shell and projecting out of one end of the tubular member, a casing hav-

ing a steam inlet and attached to the other end of the tubular member, a driving shaft rotatably supported in the casing, a flexible shaft connected to the shell and the driving shaft, the flexible shaft transferring to the driving shaft the pull exerted by the steam reacting against the revolvable head, and a device for transferring said pull from the driving shaft to the casing.

4. A soot blower adapted to be entirely removed from a boiler or furnace for use in another boiler or furnace and structurally independent thereof, said soot blower having a tubular member adapted to be inserted through a tube leading to the combustion chamber of a boiler, a hollow shell revolvably and slidably carried inside the tubular member, a steam tight packing interposed between the shell and tubular member, a head supported by said shell and projecting out of one end of the tubular member and having a jet-forming nozzle, a casing having a steam inlet and attached to the other end of the tubular member, a driving shaft rotatably supported in the casing, a flexible shaft connected to the shell and the driving shaft, the flexible shaft transferring to the driving shaft the pull exerted by the steam reacting against the revolvable head, and a device for transferring said pull from the driving shaft to the casing.

5. A soot blower adapted to be entirely removed from a boiler or furnace for use in another boiler or furnace and structurally independent thereof, said soot blower having a tubular member adapted to be inserted through a tube leading to the combustion chamber of a boiler, a hollow shell revolvably and slidably carried inside the tubular member, a steam tight packing interposed between the shell and tubular member, a head supported by said shell and projecting out of one end of the tubular member and having a jet-forming nozzle, a casing having a steam inlet and attached to the other end of the tubular member, a driving shaft rotatably supported in the casing in line with the tubular member, operating means for the driving shaft, a flexible shaft connected to the shell and the driving shaft, the flexible shaft transferring to the driving shaft the pull exerted by the steam reacting against the revolvable head, and a device for transferring said pull from the driving shaft to the casing.

6. A soot blower adapted to be entirely removed from a boiler or furnace for use in another boiler or furnace and structurally independent thereof, said soot blower having an outer casing provided with a steam inlet, an operating shaft extending into the casing, a nozzled head extending out of the casing and revolvably carried thereby, and driving connections between the operating shaft and the head, said connections including a flexible shaft.
